DRAWBAR

Lawrence M. Endres, Waunakee, Wis.

Application November 22, 1940, Serial No. 366,643

1 Claim. (Cl. 55—84)

This invention appertains to drawbars, and more particularly to drawbars for sectional harrows, and is an improvement over my prior Patent No. 1,715,063, issued to me May 28, 1929.

One of the primary objects of my present invention is to provide a strong, rugged, compact drawbar, which can be manufactured and placed upon the market at a reasonable cost.

Another salient object of my invention is to simplify the construction of the drawbar shown in my mentioned patent, whereby the same can be economically formed from steel.

A further important object of my invention is to provide novel means for hingedly connecting the side sections of the drawbar with the central main section thereof and to brace the drawbar in a novel manner, whereby undue strain on the hinges will be eliminated.

With these and other objects in view, the invention consists in the novel construction, arrangement, and formation of parts, as will be hereinafter more specifically described, claimed, and illustrated in the accompanying drawing, in which drawing:

Figure 1 is a fragmentary, top, plan view showing my improved all-steel drawbar connected with a sectional harrow.

Figure 2 is a detail sectional view taken on the line 2—2 of Figure 1, looking in the direction of the arrows, illustrating the means for bracing the drawbar and for hingedly connecting sections thereof together.

Figure 3 is a fragmentary, detail, sectional view taken on the line 3—3 of Figure 1, looking in the direction of the arrows, illustrating one of the hinges.

Figure 4 is a view similar to Figure 3, but showing one section of the drawbar folded over the central adjacent section.

Referring to the drawing in detail, wherein similar reference characters designate corresponding parts throughout the several views, the letter B generally indicates my improved drawbar for a sectional harrow H. The harrow H forms no part of my present invention and can be of the general type illustrated in my prior patent.

As shown, the harrow H includes a central section 5 and side sections 6 and 7. The forward ends of the sections 5, 6, and 7 are provided with eyes 8 for receiving coupling hooks or the like 9 carried by the drawbar B.

My novel drawbar B is of an all-steel construction, and the same embodies a main section 10 and side sections 11 and 12. These sections 10, 53

11, and 12 can be formed from steel pipe of the desired length, and the adjacent ends of the sections are hingedly connected together. Thus, the meeting ends of the sections each have welded thereto upwardly extending hinge leaves 13, and the adjacent hinge leaves are arranged in overlapping relation and are connected together by hinge bolts 14. Thus, the sections 11 and 12 can be folded over the section 10, and, obviously, the side sections 6 and 7 of the harrow can be folded with the side sections of the drawbar over the central harrow section 5.

Rigidly welded to the front face of the main drawbar section 10 adjacent the hinges are forwardly extending metal pull bars 15, and these pull bars are arranged in parallel relation and terminate in right-angularly extending, vertically disposed apertured ears 16. Welded to the upper face of the pull bars 15 and to the inner faces of the ears 16 are inwardly directed, diagonally extending, metal brace bars 17, and these brace bars have their inner ends welded to the front face of the main section 10 of the drawbar. By referring to Figure 1, it can be seen that the inner ends of the brace bars are spaced a considerable distance from the hinges, and the brace bars in conjunction with the pull bars and parts of the main drawbar section 10 form open, rugged, triangular brace frames.

30 The brace bars 17 adjacent the apertured ears 16 have welded or otherwise secured thereto eyes 19, which receive the looped ends of pull rods 20. The inner ends of the pull rods 20 are connected by a link 21, and this link or ring has connected therewith the evener bar of a doubletree 22 for permitting the connection of draft animals with the drawbar.

40 Firmly welded to the front faces of the side sections 11 and 12 of the drawbar intermediate the ends thereof are metal connecting straps 23. These straps extend inwardly and forwardly toward the forward terminals of the pull bars 15 and terminate in hinge hooks 24, which extend through the apertured ears 16 of said pull bars. 45 As the hinges and the hooks 24 are substantially in longitudinal alignment, the swinging of the side drawbar sections over the main drawbar section is permitted.

The rear faces of the drawbar sections adjacent the terminals thereof have welded or otherwise connected thereto eyes 25 for receiving the connecting hooks 9 heretofore mentioned.

From the foregoing description it can be seen that I have provided an exceptionally simple all-metal harrow drawbar, which will be of ar-

exceptionally rugged and durable construction.

Changes in details may be made without departing from the spirit or the scope of my invention, but what I claim as new is:

A drawbar for harrows comprising, a main drawbar section and side sections being formed from tubular lengths of material, with their adjacent ends normally in abutting relation, overlapping hinge leaves rigidly secured to the upper faces of the adjacent ends of said sections, hinge bolts pivotally connecting the overlapping leaves together, forwardly projecting pull bars rigidly secured to the ends of the main drawbar section, the forward ends of said pull bars terminating in

5 apertured ears, diagonally extending brace bars rigidly secured to the ends of the pull bars and to the main section inwardly of its terminals, pull links connected with the brace bars, inwardly directed straps rigidly secured to the side drawbar sections intermediate the ends thereof, and hooks formed on said straps received in said apertured ears.
